United States Patent

Des. 236,809
Patented Sept. 16, 1975

236,809

CLOCK

Richard Silva, 835 Serra Drive,
San Leandro, Calif. 94578

Filed Mar. 27, 1974, Ser. No. 455,495

Term of patent 14 years

Int. Cl. D10—01

U.S. CL. D10—6

FIG. 1

FIG. 2

FIG. 3

FIG. 4

FIG. 5

FIG. 1 is a front elevational view of a clock showing my new design, the rear being plain and unornamented;

FIG. 2 is a top plan view thereof;

FIG. 3 is a bottom plan view thereof;

FIG. 4 is a bottom plan view thereof; and

FIG. 5 is a right side elevational view thereof.

I claim:

The ornamental design for a clock, substantially as shown and described.
